UNITED STATES PATENT OFFICE.

DANIEL W. COOPER, OF LOS ANGELES, CALIFORNIA.

PIPE-TONGS.

1,271,671.

Specification of Letters Patent. Patented July 9, 1918.

Application filed August 18, 1917. Serial No. 186,941.

To all whom it may concern:

Be it known that I, DANIEL W. COOPER, a citizen of the United States, residing at Los Angeles, in the county of Los Angeles and State of California, have invented certain new and useful Improvements in Pipe-Tongs, of which the following is a specification.

This invention relates to pipe tongs or wrenches; and an object thereof is to provide a pipe wrench which may be placed around a pipe and effectively grip it substantially entirely around the pipe; to provide a wrench by which great force can be applied to the pipe without crushing or otherwise deforming it; to provide a wrench simple in construction and operation and generally, to provide a wrench of great efficiency of action.

I accomplish these objects by a structure whose typical form is set forth in the following specification, wherein I describe a preferred specific form of wrench embodying my invention. For the purpose of this specification I refer to the accompanying drawings in which—

Figure 1 is plan section of a wrench embodying my invention; Fig. 2 is a section taken on line 2—2 of Fig. 1; Fig. 3 is a detail section taken on line 3—3 of Fig. 1; Fig. 4 is a detail section taken on line 4—4 of Fig. 2; and Fig. 5 is a reduced plan of the whole length.

In the drawings the numeral 10 designates an inner annular pipe gripping member composed of two halves 11 and 12, which are drawn together and held together by wedges 13 which pass vertically through inter-engaging extensions 11^a and 12^a as is best shown in Figs. 2 and 4. The inner surfaces of members 11 and 12 are provided with ratchet teeth 14, preferably by having pieces 15 of hard steel set into their inner surfaces, the pieces 15 carrying the ratchet teeth. The outer surface of this inner annular member 10 is also provided with ratchet teeth 16; and ratchet blocks 17 have ratchet teeth 18 to engage the teeth 16. Ratchet blocks 17 are carried by the outer operating ring 20 of the device; and springs 21 press the ratchet blocks into proper engagement. This outer operating ring 20 is also made in two halves 23 and 24 secured together by pins 22 which pass vertically

through inter-engaging extensions 23^a and 24^a of the halves 23 and 24. The halves 23 and 24 are rotatable around and upon the inner member 10, working in the annular circumferential groove 26 in the inner annular member 10. This groove may have 60 overhanging outside walls 27. A handle 28 extends from one of the halves 23.

When the device is put into use, the inner annular member 10 and outer ring 20 are assembled around the pipe 30 as shown in the drawings and the wedges 13 are put in place so as to draw the two halves of this inner member together and so as to draw the ratchet teeth 14 into tight engagement with the pipe all around. Oscillation of the outer ring, by means of handle 28, will then cause the rotation of the inner member and of the pipe in the direction indicated by the arrow in Fig. 1. If it is desired to cause rotation in the opposite direction it is only necessary to turn the wrench over; that is, to turn each part face for face or end for end. To take the wrench off the pipe it is only necessary to put the parts in the relative position shown in Fig. 4. Then remove the wedges and either pin, then swing open on the other pin acting as a hinge. To put the wrench on a pipe, it is only necessary to reverse the operation. When the wrench is off the pipe, each outer ring half holds its corresponding inner member half; the inner halves are ordinarily never removed from the outer halves except for repairs.

It will be seen that a feature of my device is the annular inner member which is immovably placed upon the pipe with its teeth gripping the pipe all around, without any danger of crushing or deforming the pipe, and without the necessity of the pipe engaging the teeth changing their grip upon the pipe each time the wrench handle is moved back and forth. The outer operating ring and handle move back and forth and, through the medium of the ratchet connection, move the inner member always in the same direction. This ratchet connection may be of any desired form that will give a one-way movement; I have shown my particular form of ratchet mechanism as being convenient and effective.

I give the above written description as indicative of my invention and not in a limitative sense. The device may be modified and

varied without departing from the invention as set forth in the following claims.

Having described a preferred form of my invention, I claim:

- 5 1. A pipe wrench, embodying an inner pipe engaging ring formed of a plurality of separable segments and means to hold the segments together around a pipe, and an outer operating ring carrying the inner ring revolute therein, said outer ring formed of a similar number of separable segments and means to hold the segments together, and the segments of one ring being held in the segments of the other to be removable therefrom only by endwise movement of one segment in the other.
- 10 2. A pipe wrench, embodying an inner pipe engaging ring formed of a plurality of separable segments and means to hold the segments together around a pipe, and an outer operating ring carrying the inner ring revolute therein, said outer ring formed of a similar number of separable segments and means to hold the segments together, one of said rings having an annular groove with overhanging edges in which the other ring is revolutely held so that the segments of one ring are only removable from the segments of the other by relative endwise movement, and means mounted on the outer ring for imparting rotation to the inner ring.
- 15 3. A pipe wrench, embodying an inner pipe engaging ring formed of a plurality of separable segments and means to hold the segments together around a pipe, and an outer operating ring carrying the inner ring revolute therein, said outer ring formed of a similar number of separable segments and means to hold the segments together, one of said rings having an annular groove with overhanging edges in which the other ring is revolutely held so that the segments of one ring are only removable from the segments of the other by relative endwise movement, said holding means for the inner ring being accessible when the outer ring is mounted in position.
- 20 4. A pipe wrench, embodying an inner pipe engaging ring formed of a plurality of separable segments and means to hold the segments together around a pipe, and an outer operating ring carrying the inner ring revolute therein, said outer ring formed of a similar number of separable segments and means to hold the segments together, one of said rings having an annular groove with overhanging edges in which the other ring is revolutely held so that the segments of one ring are only removable from the segments of the other by relative endwise movement, said holding means for the inner ring being accessible when the outer ring is mounted in position.
- 25 5. A pipe wrench, embodying an inner pipe engaging ring formed of a plurality of separable segments and means to hold the segments together around a pipe, and an outer operating ring carrying the inner ring revolute therein, said outer ring formed of a similar number of separable segments and means to hold the segments together, one of said rings having an annular groove with overhanging edges in which the other ring is revolutely held so that the segments of one ring are only removable from the segments of the other by relative endwise movement, said holding means for the inner ring being accessible when the outer ring is mounted in position.
- 30 6. A pipe wrench, embodying an inner pipe engaging ring formed of a plurality of separable segments and means to hold the segments together around a pipe, and an outer operating ring carrying the inner ring revolute therein, said outer ring formed of a similar number of separable segments and means to hold the segments together, one of said rings having an annular groove with overhanging edges in which the other ring is revolutely held so that the segments of one ring are only removable from the segments of the other by relative endwise movement, said holding means for the inner ring being accessible when the outer ring is mounted in position.

outer operating ring carrying the inner ring revolute therein, said outer ring formed of a similar number of separable segments and means to hold the segments together, one of said rings having an annular groove with overhanging edges in which the other ring is revolutely held so that the segments of one ring are only removable from the segments of the other by relative endwise movement, and means mounted on the outer ring for imparting rotation to the inner ring.

4. A pipe wrench, embodying an inner pipe engaging ring formed of a plurality of separable segments and means to hold the segments together around a pipe, and an outer operating ring carrying the inner ring revolute therein, said outer ring formed of a similar number of separable segments and means to hold the segments together, one of said rings having an annular groove with overhanging edges in which the other ring is revolutely held so that the segments of one ring are only removable from the segments of the other by relative endwise movement, said holding means for the inner ring being accessible when the outer ring is mounted in position.

In witness that I claim the foregoing I have hereunto subscribed my name this 7th day of August 1917.

D. W. COOPER.

Witness:

JAMES T. BARKELEW.
